185,260

PORTABLE SUPPORT FOR A CAMERA AND LIGHT BAR OR SIMILAR ARTICLE

Louis E. Beyer, Chicago, Ill., assignor to Master Photo
Equipment Company, a partnership consisting of Louis
E. Beyer, Peter J. Maher, and Hugo Sonnenschein, Jr.

Application October 24, 1958, Serial No. 53,133

Term of patent 14 years

(Cl. D61—1)

Fig. 1 is a side elevational view of a portable support for a camera and light bar or similar article, showing my new design;

Fig. 2 is a top plan view;

Fig. 3 is a cross-sectional view taken generally along line 3—3 in Fig. 1;

Fig. 4 is an end elevational view looking from the left in Fig. 1; and

Fig. 5 is an end elevational view thereof looking from the right in Fig. 1.

I claim:

The ornamental design for a portable support for a camera and light bar or similar article, as shown.
